UNITED STATES PATENT OFFICE.

HERMAN J. SCHOEN, OF BROOKLYN, NEW YORK.

POWER PLATE-PRINTING PRESS.

No. 813,241.

Specification of Letters Patent.

Patented Feb. 20, 1906.

Application filed June 8, 1905. Serial No. 264,259.

To all whom it may concern:

Be it known that I, HERMAN J. SCHOEN, a citizen of the United States, and a resident of Brooklyn, in the county of Kings and State 5 of New York, have invented certain new and useful Improvements in Power Plate-Printing Presses, of which the following is a specification.

My invention relates to power printing-
10 presses, particularly to that class known as power "plate-printing" presses.

It has for its object to provide a power plate-printing press having means for automatically inking, rough-wiping, and polishing
15 ing the plate.

It has for a further object to provide a device of the character set forth embodying advantages in point of perfect operation, simplicity, and strength.

20 In the drawings, Figure 1 is a side elevation of my improved press. Fig. 2 is a rear elevation of the same. Fig. 3 is a fragmentary detail sectional view, on an enlarged scale, showing the inking, rough-wiping, and polishing mechanism. Fig. 4 is a fragmentary detail sectional view on the line 4-4 of Fig. 3 looking in the direction of the arrow. Fig. 5 is a fragmentary sectional view taken on the line 5-5 of Fig. 4 looking downward.

25 Fig. 6 is a diagrammatic view showing the means for operating the powdering-pad. Fig. 7 is a perspective view of the powdering-pad detached. Fig. 8 is a fragmentary sectional view, on an enlarged scale, taken on the line 8-8 of Fig. 1 looking forward. Fig. 9 is a fragmentary sectional view, on an enlarged scale, taken on the line 9-9 of Fig. 1, showing the guideways for the reciprocating plank.

30 In all the figures of the drawings illustrating my invention like reference characters designate corresponding parts.

Referring to the drawings, 1 designates the supporting-frame, comprising a base-plate 2, spaced rear vertical plates 3, and spaced
45 front vertical plates 4.

The driving-shaft 5 is mounted between one of the plates 3 and the standard-bearing 6 and carries the usual drive-pulley 7, idler 8, and fly-wheel 9. On the inner end of the
50 drive-shaft 5 is keyed the drive-gear 10, meshing with larger gears 11 and 12. The gear 11 is mounted on the horizontal cross-shaft 11^a, which has a similar gear mounted on its opposite end, transmitting power
55 through an idle gear 14, mounted on the stub-shaft 14^a, to the gear 15, which is a coun-

terpart of the gear 12. It is obvious from the foregoing description that the gears 12 and 15 will be caused to rotate simultaneously at the same speed and in the same direction, thus causing the box-cams 16 and 17, carried on short shafts 18 and 19, respectively, keyed to the gears 12 and 15, respectively, to rotate simultaneously and at the same speed.

60 The rollers 20 and 21, mounted on the laterally-projecting pins 22, travel in the cam-grooves 23 of the box-cams. The pins 22 are formed integral with the lever-arm 24, the forward end of which is mounted on a fixed pivot 25, while the rearward end 26 has pivoted thereto a link 27, which in turn is pivoted at 28 to a reciprocating arm 29, having a slot 29^a in its rear end engaged by a fixed cross-pin 30 and having a pivotal connection at 31 with the reciprocating plank 32. It will be understood that through the rotation of the box-cams 16 and 17 the arm 24 will be turned on its pivot and its rear end through the medium of the link 27 and slot-
70 75 80 85 carrying the plank 29 will lower and raise the plank carrying the plate.

Wrist-pins 33 are provided on the gears 11 and 13 and carry rearward ends of rods 34, the forward ends of which are carried on pins 35, projecting laterally from the pivoted impression-block 37.

I will now describe the means for inking, rough-wiping, and polishing the plate from which an impression is to be taken and which
90 is firmly secured to the plank 32 in any suitable manner and is therefore carried down with it in its descent, but does not touch the rough-wiper or polishers as it descends, but only when coming up after leaving the inking-roll. All of this mechanism is driven through a small gear 38, fixed to a short shaft 39, which carries a worm 40. This worm 40, meshing with a worm-wheel 41, causes the horizontally-disposed shaft 42 to rotate. The
95 forward end of this shaft carries a bevel-gear 43, which meshes with a bevel 44, fixed to a shaft 45, carrying a spool 46, on which the rough-wiping material is wound after being used. Power is imparted to the vertical
100 shaft 47 through the medium of the gear 48, mounted on its lowermost end, and the upper end of said shaft carries a double bevel 49, meshing with a bevel 50 and a bevel 51. The bevel 50 is fixed to a cross-shaft 51^a, having a gear 52 secured on its inner end and meshing with a similar gear 53, mounted on
105 110

the shaft 54. This shaft 54 is mounted in suitable bearings and carries on its rear end the gear 55, meshing with gears 56 on the ends of shafts 57, mounted on the reciprocatory sliding box 58 and carrying on their rear ends polishers 59, each polisher comprising a disk and the polishing-surfaces of said disk being flush. The reciprocatory sliding block 60 is mounted in grooves or guideways 61, formed in the plates 4, and is caused to recede from the path of travel of the plate during its descent by means of the pivoted forked arm 62, one end thereof being pivoted between spaced ears 63 on the reciprocatory block 60 and the other end engaging the pivot-bolt 64, projecting from the reciprocatory sliding block 58. The outer end of the forked arm 62 has spaced ears disposed at right angles to the body thereof and has mounted between them on a cross-pin the roller 65, which travels on the face of the cam-disk 66 on the shaft 67, and as the roller rides up on the highest point of the cam the inner ends of the forked arm are drawn forward, drawing the blocks carrying the polishers and rough-wipers away from the path of the plate as it starts to descend. The cam-disk 66 is driven by the gear 51 on the shaft 67. I employ the spring 68 to normally keep the reciprocatory rough-wiper and the reciprocal rotary polishers in the path of the plate. I employ as a rough-wiper a strip of fabric, such as cheese-cloth, and bring it into contact with the plate in such a manner as to present a clean portion of the cloth to the plate on each ascent thereof. I accomplish this by driving the roller 70 through the gear 44 and keep the fabric taut at all times by means of the friction-hub 71 and the adjustable friction-band 72. Rollers 73, mounted in the spring-press arm 73^a, contact with and keep the fabric taut when the block 60 recedes. The belt 74 runs over the grooved pulley 75 on the shaft 47 and the grooved pulley on the shaft of the ink-feed roll 76, driving said roll, which receives ink from a fountain 77 and distributes it on the spring-pressed inking-roller 78. I mount the recessed disk 79 on the horizontal shaft 42, and on the periphery of said disk runs a roller 80, mounted on the lower end of a rocking arm 81, which carries on its upper end the powder-pad 82, provided with a wire fabric on its rubbing-surface. From this construction it will be understood that when the roller 80 comes opposite the recess 79^a the spring will force it therein and the powder-pad on the upper end of the arm 81 will be swung laterally back and forth across the polishers, distributing chalk or whiting over their polishing-surfaces, and the powder-pad will be returned to its normal position again by the roller riding out of the recess.

What I claim, and desire to secure by Letters Patent, is—

1. In a power plate-printing press, a reciprocal plank adapted to carry a plate, an automatically-reciprocal polisher comprising a plurality of concurrently-rotatable disks having their polishing-surfaces flush, automatically-reciprocal cleaning means and inking means, substantially as described. 70
2. In a power plate-printing press, a reciprocal plank adapted to carry a plate, an automatically-reciprocal polisher, comprising a plurality of concurrently-rotatable disks having their polishing-surfaces flush, automatically-reciprocal dusting means, automatically-reciprocal cleaning means and inking means, substantially as described. 75 80
3. In a power plate-printing press, a reciprocal plank adapted to carry a plate, reciprocal blocks, an automatically-reciprocal polisher carried by one of said blocks and comprising a plurality of rotatable disks having their polishing-surfaces flush, automatically-reciprocal cleaning means carried by the other of said blocks, and means connecting said blocks for concurrent simultaneous reciprocal movement, substantially as de- 85 90
4. In a power plate-printing press, a reciprocal plank adapted to carry a plate, an automatically-reciprocal polisher, comprising a plurality of rotatable disks having their polishing-surfaces flush, means for causing concurrent rotary movement of said disks, and cleaning means comprising an automatically-reciprocal block and a strip of fabric adapted to be moved automatically across 95 100 the face of said block, substantially as described.
5. In a power plate-printing press, a reciprocal plank adapted to carry a plate, a polisher comprising an automatically-reciprocal 105 110 block, rotatable shafts therein and polishers on said shafts, and cleaning means comprising an automatically-reciprocal block and a strip of fabric adapted to be moved automatically across the face of said block, substantially as described.
6. In a power plate-printing press, an automatically-reciprocal polisher comprising a plurality of concurrently-rotatable disks having their polishing-surfaces flush, substantially as described. 115
7. In a power plate-printing press, an automatically-reciprocal polisher comprising a plurality of rotatable members having polishing-surfaces, dusting means adapted to be 120 reciprocated across the faces of the polisher, automatically-reciprocal cleaning means, and inking means, substantially as described.
8. In a power plate-printing press, a reciprocable plank adapted to carry a plate, a reciprocable block having concurrently-rotatable polishers comprising disks having their polishing-surfaces flush, a reciprocable block located below the first-mentioned block and 125 130

having wiping means, means connecting said blocks for simultaneous concurrent reciprocable movement and means for reciprocating said blocks, substantially as described.

5 9. In a power plate-printing press, a reciprocal plank, adapted to carry a plate, a reciprocable block having rotatable shafts provided with polishers, gearing connecting said shafts for simultaneous rotation, a reciprocable block located below the first-mentioned block and having wiping means, means connecting said blocks for simultaneous recipro-

cable movement, means for reciprocating said blocks and dusting means adapted to be automatically reciprocated across the faces of 15 said polishers, substantially as described.

Signed at the city of New York, in the county of New York and State of New York, this 6th day of June, A. D. 1905.

HERMAN J. SCHOEN.
